LUBRICATING PUMP

Alexander P. Fox, University City, and William S. Boehm, St. Louis, Mo., assignors to Lincoln Engineering Company, St. Louis, Mo., a corporation of Missouri

Application June 7, 1933, Serial No. 674,706

11 Claims. (Cl. 221—47.3)

This invention relates to lubricating pumps, and with regard to certain more specific features to hand operated, push type pumps of this class.

Among the several objects of the invention may be noted the provision of a hand pump which carries its own lubricant supply under air pressure and which is adapted to be used by push application for forcing lubricant to points such as water pumps, steering gears and the like; the provision 10 of a pump of the class described which shall effect an automatic return action after pumping strokes are manually effected, without the building up of excessive resistance to applied pressure; the provision of a pump of this class having in 15 connection with said return feature, an automatic priming feature; the provision of a form of this pump which is particularly adapted to lubricating points such as steering columns where excessive forcing of the lubricant into the 20 apparatus is not to be desired; and the provision of apparatus of this class which is simple and compact in form. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

30 In the accompanying drawing, in which is illustrated two of various possible embodiments of the invention,

Fig. 1 is a longitudinal section of one form of the invention; and

35 Fig. 2 is a longitudinal section showing another form.

Similar reference characters indicate corresponding parts throughout the several views of the drawing.

40 Referring now more particularly to Fig. 1, there is shown at numeral 1 a cylinder having a relatively fixed cap 3 and a removable base 5, the latter carrying an outlet valve body 7 which slidably accommodates a ram 9 having inlet ports 45 11 and an outlet passage 13. A ball check valve 15 in the passage 13 normally pressed to its seat by a spring 17 is adapted to be unseated by the end of the ram 9 when the ram is at the extreme left-hand end of its stroke, but to be completely seated when the ram is at the right-hand end of its stroke, as shown. A passage is provided surrounding the lower end of the ram and connecting the ports 11 with the passage 13. This connection is effective in all positions of the ram.

55 An outlet nipple 19 is screwed into the body 7

and carries an adjustable threaded bushing 21 for said spring 17. A suitable push type of coupling 23 is attached to the outlet bushing 19 and serves to deliver fluid to a receiving fitting. The fitting may be any one of known types which are used for delivering lubricant to the part requiring it. The fitting 23 is preferably of a type which, by means of various attachments, accommodates itself to various receiving fittings, but this feature being no part of the present invention, further description is deemed to be unnecessary.

The ram 9 is attached to a piston rod 25 by means of a self-aligning pin coupling 27, said piston rod 25 extending through said head 3. Upon the piston rod 25 rides a freely floating piston 29, between which and said rod are located lip packings 31 which seal against leakage increasingly well with increase in pressure. The packings 31 are retained within threaded housings 33 having suitable openings 35 therein for transmitting pressure to the packings 31.

It is the purpose of the invention to have lubricant positioned on the lower side L of the piston 29 and air on the upper side U. Lubricant is introduced into the lower side L by unscrewing the cylinder 1 from the base 5, the piston 29 being at this time at the extreme lower end of the empty cylinder 1. The cylinder 1 is then introduced into the lubricant and the reciprocating parts are drawn rearwardly. This contacts the coupling 27 with the lower member 33 and the piston may be drawn into the cylinder and thus draw lubricant after it. It is to be understood that the lubricant is of the semi-liquid viscous variety. At this time a relief valve 41 is open. After the cylinder is full, the base 5 is replaced, the same being connected with the cylinder 1 by means of the coarse screw threads 2, as shown. A packing 4 held by a support 6 serves to seal the end of cylinder 1.

Air is introduced on the upper right-hand side U of the piston 29 by means of an air receiving fitting 37 adapted to receive an air feeding chuck, the fitting 37 being associated with a check valve 39 for permitting entry of air into the cylinder 1 but preventing escape of air therefrom. The air bleeder valve 41 is used to bleed off the air should it become desirable to do this, as when refilling.

Heretofore, pumps of this general class have been provided with a return spring for forcing back the plunger after a forcing stroke has been made. We have found that this is undesirable, particularly where a push type of coupling 23 is used and forced against the receiving fitting as

a delivery stroke is made. The disadvantage that we find is that as the compression stroke continues, the reaction of the spring builds up according to the displacement, that is, the spring follows Hooke's law. Furthermore, the end of the stroke, at which the spring provides the greatest deleterious reaction, is that part of the stroke at which the highest pressure is desirable under most circumstances. Therefore, it will be seen that the spring is providing its highest reaction at the time it is least wanted, and when it is wanted, as when making return of the plunger, the spring has decreased its force due to elongation.

We have overcome the above difficulty by passing the piston rod 25 through the head 3 in a novel manner. This is done by providing the head 3 with an auxiliary cylinder 43 into which the piston rod 25 passes and wherein said rod is screwed to a continuation 45 thereof. Said continuation 45 is attached to the manual operating handle 47. A port 49 provides communication between the air within the cylinder 1 and the interior of the cylinder 43.

Interiorly of the cylinder 43, and at the junction 51 between the rods 25 and 45, there is provided a packing washer 53 which in effect, provides a piston upon which the air entering said port 49 may react. A shoulder 55 limits the upward movement of the rods 25, 45, and thus also corresponding movement of the handle 47. This shoulder presses upon a bushing 57 which is held in place by a screw cap 59.

The operation of the pump will next be described, assuming the same to be filled with lubricant and the piston 29 near the head 3.

Air pressure has been introduced above piston 29 by way of the fitting 37 and is trapped by the check valve 39. By way of piston 29, this pressure is transmitted to the lubricant beneath said piston 29. However, the pressure is not great enough to open the valve 15. It is great enough to retain the ram 9, piston rods 25, 45 and handle 47 in the upward position shown, because of the application of pressure to the small piston 53.

For operation the coupling 23 is pressed against the receiving fitting, the operator's hand being on grip 47. Pressure applied to the handle 47 results in not only forcing the coupler 23 against the lubricant receiving means but also results in the ram 9 contacting with the valve 15 thereby opening the same; whereupon the air pressure against the piston 29 forces the lubricant out through the open valve to the receiving fitting. After a suitable amount has flown, the pressure on handle 47 is released, and the air pressure on the piston 53 returns the same to the upward position, thus permitting the valve 15 to close and at the same time automatically disconnecting the coupler 23.

In Fig. 2 is shown another form of the invention in which like numerals designate like parts. This form of the invention is designed primarily for high pressure lubricating and changes are accordingly made.

Referring to said Fig. 2, numeral 61 refers to an alternate form of outlet body wherein the outlet, disc-type check valve 63 therefor, held to its seat by spring 65, is placed clear of a plunger 10, so that the plunger itself does not open said check valve. The plunger 10 is machined to a sliding seal fit in the bore of the body 61. The valve 63 opens in response to increase in pressure in the bore of body 61, as determined by plunger operation. It is to be understood that a suitable coupling corresponding to the coupling

23 is applied to the bushing 67 by means of a nipple 69. In the form of the invention shown in Fig. 2, the bushing 57 is also eliminated, thereby permitting the shoulder 55 to contact directly with the cap 59 and thus providing a longer stroke.

The operation of this form of the invention is similar to that described in connection with Figure 1, except that when the forward stroke is made, the check valve 63 is not contacted by the plunger 10 but opens due to built-up pressure caused by said plunger 10. The longer stroke permits of building up pressures in the bore of body 61 in excess and independent of the initial pressure created by piston 29. The higher pressures thus developed are required for lubricating water pumps and the like, as distinct from the lower pressure required by steering gears and the like. The form of Figure 2 is best for the former purpose, and the form of Figure 1 is best for the latter purpose.

In the form of the invention shown in Fig. 2, the advantages of the return pressure on the piston 53 are particularly to be noted. In this form of the invention, the pressure engendered in the body 61 is quite high, and increases rapidly as the movement to the left of the plunger 9 is increased. Under such conditions, any introduction of a reacting spring for effecting a return stroke is disadvantageous in that it adds an extra reaction against the manual operation.

It is known to us that the movement of the piston 53 to the left effects some increased compression on the air in the chamber U. However, if the ratio of the volume of the cylinder 43 to the volume of that part of cylinder 1 which is on the upper side of the piston 29, is low, the ratio of the increase in pressure is not as high as it would be with a spring. The point is that a spring gives no low pressure when occupying its free length and a maximum when completely compressed, whereas the air pressure provides a desirably continuous but lower pressure without excessive variations. As stroking of the pump continues the variation becomes lower because the ratio of the volume of cylinder 43 to space U becomes smaller. From time to time the air supply in chamber U may be replenished.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawing shall be interpreted as illustrative and not in a limiting sense.

We claim:

1. A pump comprising a cylinder, a floating piston therein separating the cylinder into a lubricant chamber and an air chamber, reciprocating means passing through the piston, a plunger associated with the reciprocating means within the lubricant chamber, a bushing cooperating with said plunger and having an inlet from the lubricant chamber, an outlet check valve in said bushing responsive to increased pressure effected by said plunger, a secondary cylinder, and a secondary piston means therein associated with the reciprocating means, means for exposing one side of said secondary piston to the pressure in said air chamber, whereby is effected the return of reciprocating parts after they have effected a compressing stroke.

2. A pump comprising a supply cylinder, a floating piston therein, reciprocating means passing through the piston, pump means associated with the reciprocating means and within the lubricant chamber, a secondary cylinder, a secondary piston in the secondary cylinder and on the reciprocating part, and means whereby said secondary piston is exposed to pressure from the air chamber, whereby is effected the return of said reciprocating parts after each pumping stroke thereof. 80
3. A pump comprising a supply cylinder, a floating piston therein, reciprocating means passing through the piston, pump means associated with the reciprocating means and within the lubricant chamber, a secondary piston on the reciprocating part, a secondary cylinder surrounding said secondary piston, the volumetric displacement of which secondary cylinder is relatively small in proportion to the volumetric displacement of the air chamber, and means whereby said secondary piston is exposed to pressure from the air chamber whereby is effected the return of said reciprocating parts after each pumping stroke. 85
4. A lubricating pump comprising a cylinder, a floating piston therein, reciprocating elements passing through said piston, means associated with the chamber on one side of said piston forming a lubricant outlet, an inwardly closing check valve in said outlet, a plunger associated with the reciprocating parts adapted upon reciprocation to open said valve by contact, the portion of said cylinder on the other side of the piston forming an air chamber, and means for introducing air into said chamber. 90
5. A lubricating pump comprising a cylinder, a floating piston therein forming two chambers, reciprocating elements passing through said piston, means associated with the chamber on one side of said piston forming a lubricant outlet, an inwardly closing check valve on said outlet, a plunger associated with the reciprocating parts adapted upon reciprocating to open said valve by contact, the portion of said cylinder on the other side of the piston forming an air chamber, means for introducing air under pressure into said chamber, a secondary cylinder having a communication with said first-named cylinder, and a secondary piston in said secondary cylinder and associated with the reciprocating parts, said communication transmitting air under pressure to said secondary piston whereby the return of the reciprocating parts may be effected. 95
6. A lubricant pump comprising a cylinder, a floating piston therein, reciprocating elements passing through said piston, a plunger driven by said elements, a cylinder with which said plunger cooperates to effect compression of lubricant and having an inlet opening, an outlet check valve adapted to be opened by increase in pressure, means for introducing air pressure on the opposite side of the piston, a secondary cylinder and a secondary piston in said secondary cylinder and on said reciprocating parts, and means whereby said secondary piston is exposed to the air pressure, whereby is effected the return of the reciprocating parts after each compression stroke. 100
7. A pump comprising a cylinder, a floating piston therein, reciprocating elements passing through the piston, said piston forming in said cylinder a lubricant chamber and an air chamber, outlet means through which lubricant is adapted to be forced from said lubricant chamber by said reciprocation of said elements, means for introducing air pressure into said air chamber, and means on the reciprocating elements exposed to pressure in said air chamber whereby said elements are returned after movement effecting said ejection. 105
8. A pump comprising a cylinder, a floating piston therein, reciprocating elements passing through the piston, said piston forming in said cylinder, a lubricant chamber and an air chamber, outlet means through which lubricant is adapted to be forced from said lubricant chamber by said reciprocation of said elements, means for introducing air pressure into said air chamber, means on the reciprocating elements exposed to pressure in said air chamber whereby said elements are returned after movement effecting said ejection, and a relief valve for releasing said air pressure in said air chamber, whereby indrawing of the piston into its cylinder may be effected to draw in lubricant for filling purposes. 110
9. A pump comprising a cylinder, a piston therein having lubricant on one side and compressed air on the other, said cylinder having an outlet, a check valve in the outlet, valve opening means extending freely through said piston and cylinder and adapted to be reciprocated to open and close said valve. 115
10. A pump comprising a cylinder, a piston therein having lubricant on one side and compressed air on the other, said cylinder having an outlet, a check valve in the outlet, valve opening means extending freely through said piston and cylinder and adapted to be reciprocated to open and close said valve, a secondary piston attached to said valve opening means, a secondary cylinder slidably containing said secondary piston, and means exposing said secondary piston to the compressed air to which the first-named piston is exposed, whereby is effected a return to initial positions of the valve opening means. 120
11. A pump comprising a cylinder, a free piston therein having lubricant on one side and compressed air on the other, said cylinder having an outlet, a check valve in the outlet, compressing means extending freely through said piston and cylinder and adapted to be reciprocated, an outlet cylinder having an opening communicating with the first-named cylinder and accommodating said compressing means whereby compression may be effected, a secondary piston on the compressing means, a secondary cylinder containing said piston, and means whereby said secondary piston is exposed to said compressed air, whereby may be effected the return of the compressing means after a compression stroke. 125
12. A pump comprising a cylinder, a piston therein having lubricant on one side and compressed air on the other, said cylinder having an outlet, a check valve in the outlet, compressing means extending freely through said piston and cylinder and adapted to be reciprocated, an outlet cylinder having an opening communicating with the first-named cylinder and accommodating said compressing means whereby compression may be effected, a secondary piston on the compressing means, a secondary cylinder containing said piston, and means whereby said secondary piston is exposed to said compressed air, whereby may be effected the return of the compressing means after a compression stroke. 130
13. A pump comprising a cylinder, a piston therein having lubricant on one side and compressed air on the other, said cylinder having an outlet, a check valve in the outlet, compressing means extending freely through said piston and cylinder and adapted to be reciprocated, an outlet cylinder having an opening communicating with the first-named cylinder and accommodating said compressing means whereby compression may be effected, a secondary piston on the compressing means, a secondary cylinder containing said piston, and means whereby said secondary piston is exposed to said compressed air, whereby may be effected the return of the compressing means after a compression stroke. 135
14. A pump comprising a cylinder, a piston therein having lubricant on one side and compressed air on the other, said cylinder having an outlet, a check valve in the outlet, compressing means extending freely through said piston and cylinder and adapted to be reciprocated, an outlet cylinder having an opening communicating with the first-named cylinder and accommodating said compressing means whereby compression may be effected, a secondary piston on the compressing means, a secondary cylinder containing said piston, and means whereby said secondary piston is exposed to said compressed air, whereby may be effected the return of the compressing means after a compression stroke. 140
